UNITED STATES PATENT OFFICE.

FRANCIS ALBERT CURNOW, OF PITTSBURG, KANSAS.

ROASTING-FURNACE.

1,072,920.

Specification of Letters Patent. Patented Sept. 9, 1913.

Application filed March 18, 1913. Serial No. 755,077.

To all whom it may concern:

Be it known that I, FRANCIS ALBERT CURNOW, citizen of the United States of America, residing at Pittsburg, Crawford county, Kansas, have invented certain new and useful Improvements in Roasting-Furnaces; and I do hereby declare the following to be a full, clear, and exact description of the invention, such as will enable others skilled in the art to which it appertains to make and use the same.

My invention relates to improvements in roasting furnaces, and in particular to roasting furnaces provided with mechanically operated rabble rakes.

The object of my invention is to provide means for controlling the operation of said rabble rakes according to the nature of ores being treated in roasting furnaces.

With this general object in view, and some others which will be obvious to those skilled in the art from the description hereinafter, my invention consists in the features, combinations of parts and details which will first be described in connection with the accompanying drawings and then more particularly pointed out in the claims.

In the drawings, Figure 1 is a diagrammatic plan view of a portion of a mechanical zinc ore roasting furnace equipped with rakes embodying my invention; Fig. 2 a similar longitudinal elevation, partly in section, of the same; Fig. 3 a transverse section on the line 3—3, Fig. 1; Figs. 4 and 5 are a plan and elevation, respectively, of the automatically controlled starting and stopping mechanism for the rakes.

Referring to the drawings, and particularly to Figs. 1 and 2, A indicates traveling rakes arranged to stir and rake out the ores of a suitable roasting furnace A', these rakes being carried by suitable cable cars A² running on tracks, each car being attached to an endless cable B which passes around drums C, C', so that by operating one of the drums, for example, C, each car will travel first in one direction, thence in a semicircle, as it moves around the respective drum, thence in the opposite direction around a semicircle as it moves around the other drum, thence again in the first direction and so on repeatedly, so long as the driving drum is operated. Any material,

such as ores from a roasting furnace will be moved along by the rakes to any suitable point of discharge.

Since it is not necessary to operate the rakes continuously but only at suitable intervals, which intervals, however, vary according to the nature and condition of the ores treated in the roasting furnace, I have provided automatic mechanism for starting and stopping the rakes, the mechanism being adjustable to allow the interval during which the rakes are out of operation to be varied according to the conditions to be met in actual service. Broadly considered, this automatic mechanism comprises means for rotating the cable driving drum, this means being operated from a continuously moving source of power, through the aid of a transmission gearing which may be thrown out of action by a tripping device tripped by a rake when it arrives at a predetermined position in its travel, said tripping apparatus being controlled by a suitable adjustable timing device which, after the rake is stopped, starts in operation and after the requisite interval of time for which it is adjusted, throws the transmission gearing into condition to again transmit power from the continuous source of power to the means for driving the cable drum, the rake then again commencing its travel and continuing to operate until it again reaches the predetermined position for actuating the tripping mechanism, which stops the cable drum.

In the present example, the mechanism above described generally is as follows: D is a continuously moving source of power, in this instance a main driving shaft having a pulley d over which passes a belt d' arranged to run on either a loose pulley E or a tight pulley E', these pulleys E and E' being mounted on a winding shaft E² journaled in suitable bearings, as indicated at e. For the purpose of shifting the belt d' from one pulley to the other, a belt shifter of any suitable construction is provided, this consisting in the present example of a longitudinally movable slide bar F mounted in slide boxes f and provided with upward extending prongs F' between which the belt d' passes. To the shifter F is connected one end of a bell-crank G pivoted at g, the other end of said bell-crank being connected to a

shift-rod H longitudinally slideable in suitable slide boxes h , h' , which rod H, is provided with two collars, h^2 , h^3 secured to the rod H by set screws, whereby it is possible 5 to adjust the said collars to any desired positions along the rod H and secure them in such positions.

Between the two collars h^2 , h^3 , is mounted a sleeve I slideable loosely along the rod H 10 and provided with a suitable attaching device, as for example, an eye, i, to which is secured means for shifting the said sleeve I, as will be more fully explained hereinafter. The opposite end of the rod H is pivotally 15 connected to one arm of a bell-crank K, pivoted at k and having its other arm connected to a longitudinally slideable belt-shifter L mounted in suitable slide-boxes, as indicated at l and provided with upward 20 extending prongs l' between which passes a belt M driven from a suitable pulley N on the main shaft D and arranged to pass around either a loose pulley N' or a tight pulley N^2 , according to the position of the shifter L. The pulleys N' , N^2 are mounted 25 on a counter shaft N^3 which drives the cable-driving drum C through any suitable mechanism as for example, the following: To the countershaft N^3 is fixed a pinion N^4 engaging a gear-wheel O on a shaft O' which extends to the cable drum C and is provided 30 with a bevel pinion O² in mesh with a bevel gear wheel e fixed to the drum shaft.

The belt-shifter L is extended toward the 35 path of the rakes and is connected to one arm of a bell-crank P pivoted at p and having its other arm curved to serve as a striker-arm which is in the path of the arm of the rake, and is tripped or shifted when 40 struck by the rake in its travel, or by some striking or tripping element, such as an upward projecting pin p' fixed to the rake which serves for tripping the mechanism.

The winding or timing shaft E² has two 45 portions arranged as winding drums, one portion having wound thereupon a rope, or the like as indicated at e' which rope is provided with a weight e² for a purpose herein-after explained. The other winding drum 50 portion is arranged to have wound thereupon a draft device such as a cable of rope or the like as indicated at e³ which rope passes over suitable pulleys e⁴ and extends parallel to and near the shift-rod H, its free 55 end being provided with a weight e⁵. The rope e³ is connected to the eye, i, of the sliding sleeve I, as shown in Fig. 4.

The ropes e' and e³ are so wound upon the winding drum portions of the shaft E² that 60 when the shaft E² is not driven by its tight pulley E' and belt d' the weight e² can descend and rotate the shaft E² in a backward direction, thus unwinding the rope e³, in which it is assisted by the weight e⁵ attached 65 to said rope e³.

The operation of the apparatus thus far described is as follows: When the rakes have been operated by their cable drum C to rake the ore to a desired place at the end of their longitudinal paths, the movement of said rakes will eventually bring one rake to the position where it or its tripping device, for example, the pin p', will contact with the striker arm of the bell-crank P, whereby the latter is moved in a direction to shift, the belt-shifter L so as to move the belt M from the tight pulley N^2 to the loose pulley N' , thus stopping the rakes. At the same time that the belt-shifter L is moved as above described, the bell-crank K is moved to shift the rod H in the direction of the arrow x , Fig. 4, whereby the bell-crank G at the opposite end of the rod H is moved to operate the belt-shifter F, thus shifting the belt d' from the loose pulley E to the tight pulley E' and starting the timing shaft E² in rotation. This rotation of the timing shaft causes it to wind up the ropes e' and e³ respectively whereby the weights e² and e⁵ are lifted. The winding up of the rope e² causes the sleeve I to be drawn in the direction of the arrow y, Fig. 4, moving along the rod H until said sleeve finally contacts with the collar h^2 , after which contact the rod H itself is drawn in the direction of the arrow y, Fig. 4, thus shifting the bell-cranks K and G so as to shift the belt M onto the tight pulley N^2 and the belt d' onto the loose pulley E. The rakes again start in operation to rake or stir the ore and the winding shaft E² is no longer power driven. The weights e² and e⁵ now act to draw their respective ropes e' and e³ so as to unwind them from the shaft E². The movement of the rope e³ by its weight e⁵ causes the sleeve I to slide along the rod H in the direction of the arrow x, Fig. 4, until finally said sleeve contacts with and is stopped by the collar h^3 . The apparatus remains in this condition until the rake carrying the tripping device again reaches its predetermined position for operating the striking arm of the bell-crank, P, whereupon the latter is swung to shift the belt M onto the loose pulley N' and the belt d' onto the tight pulley E' whereby the actions hereinbefore described are repeated.

It will be noted that the rakes remain inactive while the sleeve is traveling along the rod H between the two set collars h^2 and h^3 and, hence, by adjusting these collars suitably along the rod H the interval during which the rakes are idle may be adjusted to meet the desired conditions of operation, after which the action is automatic.

While the starting and stopping apparatus is shown and described as part of a combination including a roasting furnace and rabble raking device thereof, it is to be understood that such starting and stopping

apparatus may be useful in other combinations where it is desired to operate mechanism intermittently, with adjustable intervals of rest.

5 What I claim and desire to secure by Letters Patent is:

1. In a roasting furnace or the like, the combination, with the furnace, a raking apparatus arranged to stir and rake ore from the furnace, and means for driving the same, of means arranged to be actuated by the raking apparatus for automatically stopping the latter, and means set into operation upon the stopping of the raking apparatus for 15 automatically starting the raking apparatus after a predetermined interval.

2. In a roasting furnace or the like, the combination, with the furnace, a raking apparatus arranged to rake ore from the furnace and a source of power of operating said raking apparatus, of means for transmitting power from said source to the raking apparatus to actuate the latter, means arranged to be actuated by the raking apparatus for disconnecting said transmitting means from the source of power, and means operating after a predetermined time interval to connect said transmitting means with the source of power, whereby the raking apparatus is again put in action.

3. In a roasting apparatus or the like, the combination, with the furnace, a raking apparatus arranged to rake ore from the furnace, and a source of power for operating said raking apparatus, of delay-action means for automatically connecting said source of power to the raking apparatus to actuate the same, and means operated by the raking apparatus on its arrival at a predetermined position for disconnecting said raking apparatus from the source of power

and setting into action the said delay-action connecting means.

4. In a roasting apparatus or the like, the combination, with the furnace, a raking apparatus comprising a rake arranged to rake ore from the furnace, a source of power, and a transmission device connected to said raking apparatus, of a longitudinally movable rod, means connected to said rod for coupling said transmission device to and uncoupling it from the source of power, means in the path of the rake for shifting said rod in one direction, and a timing device coupled to the rod and arranged to shift it in the other direction.

5. In a roasting apparatus or the like, the combination, with the furnace, a raking apparatus comprising a rake arranged to rake ore from the furnace, a source of power, and a transmission device connected to said raking apparatus, of a longitudinally movable rod, means connected to said rod for coupling said transmission device to and uncoupling it from said source of power, a rotatable winding device, means connected to said rod for coupling said winding device to and uncoupling it from said source of power, a draft device arranged to be wound up by said winding device, stop devices carried by the said rod, a sleeve device movable along the rod between said stop devices and connected to said draft device, and means arranged in the path of the rake for shifting said rod longitudinally.

In testimony whereof I hereunto affix my signature in the presence of two witnesses.

FRANCIS ALBERT CURNOW.
